COMBINATION ARMCHAIR AND BED

Charles Machet, Lyon, France

Application January 9, 1953, Serial No. 330,490

5 Claims. (Cl. 155—49)

1

This invention relates to furniture construction. More specifically, the invention has reference to convertible furniture, wherein a chair is convertible into a bed, or vice versa.

The desirability of convertible furniture of the type stated is well appreciated, and it need not be dwelt upon at great length herein. It is believed sufficient to note that an item of furniture of the character described can be used advantageously in hospitals, sanitariums, and convalescent homes, as well as on steamships, at beach resorts, and at other locations.

However, in addition to the general desirability of converting the chair to a bed, and the bed into a chair, without requirement of the person reclining thereupon getting off the furniture piece to effect the conversion it is desirable that said person be enabled to effect the conversion without the assistance of another person, since such assistance might not be available at the particular time when the conversion is to be made.

It is, accordingly, the main object of the present invention to provide a piece of furniture so designed as to permit its conversion either into a chair or into a bed by the person reclining thereupon without the necessity of calling upon an assistant.

Another important object is to provide a piece of convertible furniture as described which will automatically extend into a full length bed when changed from a chair into a bed.

Still another important object is to provide a convertible chair and bed so designed as to permit the conversion to be effected by a simple pivotal adjustment of the component frame portions thereof.

Yet another object of importance is to provide convertible furniture as stated, wherein a back support for the bed is readily shiftable into a position wherein it will serve as a canopy frame when the furniture piece is converted into a chair.

Other objects will appear from the following description, the claims appended thereto, and from the annexed drawings, in which like reference characters designate like parts throughout the several views, and wherein:

Figure 1 is a side elevational view of a piece of furniture formed in accordance with the present invention, the full lines indicating the positions of the parts when the furniture is being used as a bed, and the dotted lines indicating the position of said parts when the furniture is prepared for use as a chair;

2

Figure 2 is a bottom plan view, the parts being illustrated as they appear when the furniture piece is in use as a bed;

Figure 3 is a rear elevational view, illustrating the structure when converted into a bed;

Figure 4 is an enlarged detail sectional view taken substantially on line 4—4 of Figure 1, illustrating a latch means embodied in the construction;

10 Figure 5 is an enlarged detail sectional view taken substantially on line 5—5 of Figure 1 and illustrating the arrangement embodied in the invention whereby a piece of canvas webbing is secured to the frame of the structure;

15 Figure 6 is a side elevational view of the complete structure as it appears when converted into a chair;

Figure 7 is a top plan view of the structure as it appears when in use as a chair; and

20 Figure 8 is an enlarged detail sectional view taken on line 8—8 of Figure 3 and illustrating a separable connection used between the back support of the structure and the frame thereof.

Referring to the drawings in detail, the structure constituting the present invention includes a plurality of connected frames which, together, form the basic components of the complete assembly. These include a front end frame, a connecting means, a back frame, and a rear end frame, each of which will be described in turn.

The front end frame has been designated generally by the reference numeral 10, and includes a pair of horizontal, parallel, tubular side rails 12 extending along the opposite sides of the chair-bed, being disposed along opposite side edges of the seat portion of the assembly when said assembly is being used as a chair. This construction is believed best illustrated in Figures 6 and 7. As will be noted from these figures, at their front ends the side rails 12 are respectively integral with depending, vertical front legs 14. At their lower ends the legs 14 are integrally connected to the opposite ends of a forwardly offset, horizontal crossbar 16, which braces the legs transversely of the structure.

The connecting means has been generally designated 18, and comprises a pair of horizontal, tubular side members 20 formed open at their front ends and closed at their rear ends by angular pivot brackets 22 that are welded or otherwise fixedly secured to the side members.

The tubular side members 20 of the connecting means are proportioned to receive the respective side rails 12 of the front end frame, the side rails extending into the open front ends of the side

members and sliding into and out of said members. When the side rails 12 are telescoped within the side members, the legs 14 of the front end frame will be in the dotted line position illustrated in Figure 1. When, however, the side rails are withdrawn to a substantial extent from the tubular side members 20, the legs 14 will be in the full line position illustrated in this figure.

Thus, the front end frame can be appropriately considered as being extensible forwardly of the assembly constituting the present invention, and will be so extended when the assembly is to be used as a bed. When the structure is to be used as a chair, the end frame 10 is retracted relative to the connecting means to the dotted line position illustrated in Figure 1.

The respective brackets 22 are formed with pivot bolt-receiving openings 24 aligned transversely of the structure, for pivotal connection of a back frame, generally designated 26, to the rear end of the connecting means.

The back frame 26 is of tubular formation throughout, and is provided with a pair of parallel side bars 28, the front ends of which terminate at the respective brackets 22 of the main frame. The side bars 28 extend rearwardly of the brackets 22 in the general direction of the rear end of the structure, and are pivoted at their front ends upon the respective brackets by means of pivot bolts 29. Thus, the side bars 28 may swing between extreme positions illustrated in dotted and full lines in Figure 1. In the dotted line position of the side bars, said side bars are extended upwardly and rearwardly of the connecting means, to cooperate in forming a chair back when the assembly constituting the present invention is to be converted for use as a chair. In the full line positions of the side bars, said side bars are disposed horizontally and are aligned coaxially with the side rails 12 and tubular side members 20 to cooperate therewith in forming the elongated, longitudinally extended side frame portions of a bed.

The rear ends of the side bars 28 of the back frame are integral with the opposite ends of a cross member 30 extending transversely of the structure (Figure 2) at the rear end of said structure.

Forwardly of the pivotal connections 29, the back frame 26 is formed with downwardly offset portions 32, which are integral with the front ends of the respective side bars 28 and merge into upper chair leg portions 34. The chair leg portions 34, in turn, merge at their front ends into lower chair leg portions 36 of longitudinally curved formation.

The relationship of the side bars 28, upper chair leg portions 34 and lower chair leg portions 36 to the pivot axis 29 of the back frame 26 is believed to be of importance. As particularly well shown in Figure 1, the side bars 28 are disposed radially of said pivot axis, while the upper chair leg portions 34 are offset radially of the pivot 29. The lower chair leg portions 36, in this connection, are arranged as arcs having the pivot axis 29 of the back frame as their center, said lower chair leg portions being shiftable about said center between extreme positions shown in full and dotted lines, respectively, in Figure 1. In the full line position of the lower chair leg portions 36, and of the upper chair leg portions 34, said portions 36 and 34 form the intermediate legs of an elongated bed. In the dotted line position of these parts, they cooperate to provide the rear legs of a chair.

Integral with and extending between the lower or rear ends of the leg portions 36 is a cross brace 38 disposed transversely of the assembly constituting the present invention (see Figure 2).

Means is provided for holding the back frame 26 against movement relative to the connecting means 18 in either extreme position to which the back frame is adjusted. To this end, a latch or detent is mounted upon one side of the structure, the construction thereof being illustrated in detail in Figure 4. This latch includes a tubular latch housing 40 mounted rigidly upon the front end of one of the side bars 28. A latch rod 42 provided with a handle is slidably mounted within the housing 40, and is surrounded within the housing by a coil spring 44. At its front end the rod 42 is provided with a head 46, the spring 44 abutting at one end against said head and at its other end against the end wall of the housing, thus to urge the head 46 forwardly into engagement with a selected notch 48 of the latch bracket 2 contiguous thereto. When the head 46 is engaged in one notch 48, it retains the back frame in the dotted line position illustrated in Figure 1. When, however, the head 46 is engaged in the other notch 48, it retains the back frame in the full line position illustrated in Figure 1.

A rear end frame has been generally designated 50 and is best shown in Figures 3 and 7, said rear end frame being also illustrated to advantage in Figure 6.

The rear end frame 50 is formed from a plurality of pivotally connected members, and includes a pair of main support bars 52 which are pivotally connected, as at 54, to the opposite ends of the cross member 30 of the back frame. The bars 52, when in the position thereof illustrated in Figure 3, define the rear end legs of the bed into which the illustrated assembly can be converted.

At their other ends the respective main support bars 52 of the rear end frame are pivotally joined at 56 to the ends of crossing intermediate links 56. The links 56, in turn, are pivotally connected at their other ends, as at 60, to the outer ends of end links 62, 64.

The end links 62 and 64 are lapped at their inner ends, and are pivotally connected to one another by a pin 65. That end of the link 62 which is connected to the link 64, in this connection, is formed integrally with a laterally extended, angular tongue 66 (Figures 3 and 8), which is adapted to enter a longitudinal slot 68 formed medially between the opposite ends of the cross member 30.

A chain 70 is connected to one of the intermediate links 56, and carries a drop pin 72. The drop pin 72 is extendable through openings formed in the respective links 56, said openings registering when the rear end frame is adjusted to the position illustrated in Figure 3, for supporting the bed at one end. Thus, by inserting the drop pin 72 in the registering openings of the links 56, the rear end frame may be suitably braced against movement when adjusted to said position.

When, however, the assembly is to be converted into a chair (Figures 6 and 7), the drop pin 72 is removed from the openings in which it was previously inserted, and this will permit the component parts of the rear end frame to be shifted to the position illustrated in Figure 7. To adjust said parts of the rear end frame to the position of Figure 7, it is merely necessary to remove the tongue 66 from its associated slot 68, after which the tongue 66 may be gripped as a handle and

pulled toward the front end of the assembly. This will cause the main support bars 52 to swing inwardly toward one another, over the cross member 30, until said main support bars 52 are aligned longitudinally with their associated intermediate links 56.

In this position of the rear end frame, it serves as a canopy frame, over which a canopy 74 of canvas or similar material can be placed when the assembly is being used as a chair.

At the intersection of the respective side rails 12 and front legs 14, the front end frame 10 is provided with downwardly and rearwardly extended ears 76 that are rigidly mounted upon the front end frame and are formed with openings aligned transversely of the structure. The openings of the ears 76 are adapted to receive (Figures 1, 2 and 6) the outwardly and laterally projected front ends 78 of parallel extension rods 80. The extension rods 80 are of generally elongated formation, and are provided at their rear ends with outwardly and laterally extended rear end portions 82 received in openings formed in the respective chair leg portions 34 of the back frame. Thus, the front end frame 10 is pivotally linked with the back frame 26.

A canvas extension web 84 extends between and is connected along its opposite side edges to the respective extension rods 80 (Figures 2 and 6), so as to support one end of the reclining person's body when the assembly is being used as a bed. To prevent the extension web from shifting longitudinally of the extension rods, tie loops 86 are connected to the front corners of said web, and are passed around the respective front legs 14.

A main web of canvas or like material has been designated 88, and is formed to such a length as to extend from the front end of the connecting means 18 to the rear end of the back frame 26. The main web is connected along its sides both to the connecting means and back frame, and for the purpose of connecting said main web to the tubular side members 28 of the connecting means, the main web is formed with front side flaps 89 (Figure 5), extending about the side members 28.

A series of springs 90 disposed transversely of the assembly is so arranged that each spring is connected at one end to the side flap 89 contiguous thereto. At their other ends the springs are connected to the respective side edges of an elongated, reinforcing web 92 that underlies the main web 88, and extends substantially from end to end of the main web. As a result, the main web is tensioned transversely of the assembly, so as to afford a strong, comfortable support for the reclining person, whether said assembly is being used as a chair or as a bed.

For the purpose of permanently securing the reinforcing web 92 to the main web, stitching 94 is employed, extending longitudinally of the opposite sides of said reinforcing web.

A rear series of springs 98 is employed, said springs being connected at one end to rear side flaps 96 formed upon the main web, and at their other ends to the opposite side edge portions of the reinforcing web 92. The rear side flaps 96 extend about the side bars 28 of the back frame, thus to tension the main web transversely of the back frame and cooperate with the tensioned front end portion of the main web in supporting, comfortably and yet strongly, the body of the reclining person.

The main web is also connected to the cross member 30 of the back frame, and to this end a rear end flap 100 is provided upon the main web,

said rear end flap extending about the cross member 30 and being notched midway between its opposite ends (Figure 3) to provide clearance for the tongue 66. The rear end flap 100 is connected to a plurality of rear end springs 102, disposed longitudinally of the assembly (Figure 2) and connected at their inner ends to a rear end reinforcing strip 104 stitched or otherwise secured to the under side of the main web 88.

10 Considering the use of the structure, it will first be assumed that the structure is being used as a bed (full line position, Figure 1). As a first step, the person reclining thereupon disengages the latch from the lower notch 48 to free the back frame 26 for swinging movement relative to the connecting means. By shifting to a sitting position, said person then disposes his entire weight upon the front end portion of the main web 88, and the pressure exerted downwardly upon the main frame by the person so doing causes the entire assembly to rock forwardly upon the lower, arcuate leg portions 36. If necessary, this forward rocking movement can be aided by a reclining person, who may shift his or her weight forwardly of the assembly.

As the connecting means rocks forwardly upon the leg portions 36, the upper leg portions 34 are shifted downwardly from the full line position illustrated in Figure 1 to the dotted line position illustrated in this figure. This causes the extension rods 80 to pull rearwardly upon the extension frame 10, causing said frame to be retracted into the connecting means.

At the same time, the forward rocking movement upon the lower leg portions 36 is effective to swing the back frame to the dotted line position illustrated in Figure 1, thus to cause the entire assembly to be converted for use as a chair.

Thereafter, it is merely necessary, if the user desires a canopy, to pull the rear end frame 50 forwardly of the back frame to the position illustrated in Figures 6 and 7, thereby to provide a canopy frame.

When the assembly is to be used once again as a bed, the user disengages the latch from the upper notch 48, and presses rearwardly with his head or hand upon the upper portion of the back frame 26, thus causing the back frame to swing downwardly to the full line position illustrated in Figure 1, the action being effective to extend the front end frame 10 once again. The latch is then engaged once again in the lower notch 48.

It is believed to be of importance, in this connection, that the conversion of the assembly from a chair into a bed causes the over-all length of the assembly to be extended to provide a full length bed. Subsequently, the conversion of the bed into the chair is effective to shorten the portion of the structure that supports the pelvis and lower limbs of the user, to provide a chair formed with a seat portion of a proper length that will support the user of the chair in a comfortable, seated position.

65 It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that

may be permitted within the scope of the appended claims.

What is claimed is:

1. In convertible furniture, a generally horizontal connecting means for supporting the lower part of the body of a user; front support legs depending from one end thereof and slidably connected thereto; and a rigid back frame pivotally connected intermediate its ends to the connecting means, said back frame including a pair of side bars having means thereon for supporting the upper part of said body, and said back frame having a pair of rear support legs having upper leg portions rigid at one end with and offset rearwardly from the rest of respective side bars in parallel relation thereto, said rear support legs having supporting surface-engaging lower leg portions rigid with the other ends of the upper leg portions, and curved in an arc having the pivot point of the side bars as its center, rigid means pivotally connected between the front and rear legs, said back frame being rockable on the lower leg portions between extreme positions in one of which the side bars are aligned horizontally with the connecting means to cooperate therewith in forming a bed, and in the other of which the side bars are inclined for coaction with the connecting means in forming a chair.

2. In convertible furniture, a generally horizontal connecting means for supporting the lower part of a user's body; a front end frame telescoped at one end in one end of the connecting means for extending the length of the front end frame, said front end frame including a pair of depending front support legs; a back frame pivotally connected intermediate its ends to the other end of the connecting means and said front end frame, said connecting means and one end of the back frame having means thereon for supporting the upper part of a user's body and having a pair of rear support legs at its other end, the rear support legs having lower leg portions curved in an arc having the pivot point of the back frame as its center, the back frame being rockable on said lower leg portions between extreme positions in one of which its first-named end is disposed substantially horizontally to coact with the connecting means in forming a bed and in the other of which said first-named end of the back frame is inclined to coact with the connecting means in forming a chair; and extension rods pivotally connected at their opposite ends to and extending between the rear support legs and front end frame, respectively, said rods being arranged to translate pivotal movement of the back frame between the first and second-named extreme positions thereof into slidable movement of the front end frame between front end frame extended and retracted positions thereof, respectively.

3. In convertible furniture, a generally horizontal connecting means for supporting the lower part of a user's body; a front end frame telescoped at one end in one end of the connecting means for extending the length of the front end frame, said front end frame including a pair of depending front support legs; a back frame pivotally connected intermediate its ends to the other end of the connecting means and said front end frame, said connecting means and one end of the back frame having means thereon for supporting the upper part of a user's body and having a pair of rear support legs at its other end, the rear support legs having lower leg portions curved in an arc having the pivot point of the back frame as its cen-

the back frame as its center, the back frame being rockable on said lower leg portions between extreme positions in one of which its first-named end is disposed substantially horizontally to coact with the connecting means in forming a bed and in the other of which said first-named end of the back frame is inclined to coact with the connecting means in forming a chair; extension rods pivotally connected at their opposite ends to and extending between the rear support legs and front end frame, respectively, said rods being arranged to translate pivotal movement of the back frame between the first and second-named extreme positions thereof into slidable movement of the front end frame between front end frame extended and retracted positions thereof, respectively; and said second named means comprising webbing mounted upon said connecting means, back frame, and front end frame, respectively, for covering the same.

4. In convertible furniture, a generally horizontal connecting means for supporting the lower part of a user's body; a front end frame telescoped at one end in one end of the connecting means for extending the length of the front end frame, said front end frame including a pair of depending front support legs; a back frame pivotally connected intermediate its ends to the other end of the connecting means and said front end frame, said connecting means and one end of the back frame having means thereon for supporting the upper part of a user's body and having a pair of rear support legs having lower leg portions curved in an arc having the pivot point of the back frame as its center, the back frame being rockable on said lower leg portions between extreme positions in one of which its first-named end is disposed substantially horizontally to coact with the connecting means in forming a bed and in the other of which said first-named end of the back frame is inclined to coact with the connecting means in forming a chair; extension rods pivotally connected at their opposite ends to and extending between the rear support legs and front end frame, respectively, said rods being arranged to translate pivotal movement of the back frame between the first and second-named extreme positions thereof into slidable movement of the front end frame between front end frame extended and retracted positions thereof, respectively; said second named means comprising webbing mounted upon said connecting means, back frame, and front end frame, respectively, for covering the same; and latch means adapted for locking the back frame against movement from selected positions to which it is pivotally adjusted relative to the connecting means.

5. In convertible furniture, a generally horizontal connecting means for supporting the lower part of a user's body; a front end frame telescoped at one end in one end of the connecting means for extending the length of the front end frame, said front end frame including a pair of depending front support legs; a back frame pivotally connected intermediate its ends to the other end of the connecting means and said front end frame, said connecting means and one end of the back frame having means thereon for supporting the upper part of a user's body and having a pair of intermediate support legs at its other end, the intermediate support legs having lower leg portions curved in an arc having the pivot point of the back frame as its cen-

ter, the back frame being rockable on said lower leg portions between extreme positions in one of which its first-named end is disposed substantially horizontally to coact with the connecting means in forming a bed and in the other of which said first-named end of the back frame is inclined to coact with the connecting means in forming a chair; extension rods pivotally connected at their opposite ends to and extending between the intermediate support legs and front end frame, respectively, said rods being arranged to translate pivotal movement of the back frame between the first and second-named extreme positions thereof into slidable movement of the front end frame between front end frame extended and retracted positions thereof, respectively; a rear end frame including a pair of support bars pivotally connected at one end to the back frame for swingable adjustment between

10 5

one position in which said support bars form the rear end legs of a bed and in the other of which they form a part of a frame for a chair canopy; said second named means comprising webbing mounted upon said connecting means, back frame, and front end frame, respectively, for covering the same; and latch means mounted upon the back frame and adapted for locking the back frame against movement from selected positions to which it is pivotally adjusted relative to the connecting means.

CHARLES MACHET.
